(57) **CLAIM**

The ornamental design for doll with an open mouth, as shown and described.

DESCRIPTION

FIG. 1 is a front elevational view of a doll with an open mouth showing our new design;

FIG. 2 is a rear elevational view thereof;

FIG. 3 is a left side elevational view thereof, the opposite side being a mirror image thereof;

FIG. 4 is a top plan view thereof;

FIG. 5 is a front elevational view of another embodiment of the doll with an open mouth of FIGS. 1-4 showing our new design;

FIG. 6 is a rear elevational view of the embodiment shown in FIG. 5;

FIG. 7 is a top plan view of the embodiment shown in FIG. 5;

FIG. 8 is a left side elevational view of the embodiment shown in FIG. 5; and,

FIG. 9 is a right side elevational view of the embodiment shown in FIG. 5.
